[57] **ABSTRACT**

An improved chain saw and method of operating a chain saw in a cold, humid environment where ice may form in the carburetor of the chain saw engine is disclosed. An ice-inhibiting substance is mixed with the fuel and lubricating fluid and introduced into an interior portion of the carburetor in conjunction with the combustible mixture of fuel, lubricating fluid, and air during operation of the two-cycle internal combustion chain saw engine in order to inhibit the formation of ice therein. The ice inhibiting means may be pre-mixed with the lubricating fluid.

**METHOD AND APPARATUS FOR OPERATING AN
ENGINE-DRIVEN CHAIN SAW IN AN
ENVIRONMENT WHERE ICE MAY FORM IN THE
CARBURETOR OF THE ENGINE**

BACKGROUND OF THE INVENTION

This invention relates generally to a novel method and apparatus for operating a chain saw in a relatively cold environment. More particularly, this invention provides a chain saw including an ice inhibitor which substantially inhibits the formation of ice in the internal portion of a carburetor of the two-cycle engine of the chain saw to substantially prevent carburetor blockage during operation of the engine in cold, humid atmospheric conditions.

Because of the substantial increase in the use of gasoline engines of the two-cycle type for chain saws by the general public and by the logging and lumber industry, satisfactory, trouble-free engine performance is extremely desirable in the operation of such engines. Two-cycle chain saw engines giving dependable performance can be manufactured in small sizes, making their use ideal for service in remote regions of the world wherein large scale logging operations have begun to take place.

In the operation of gasoline engines of the two-cycle type, a lubricating oil-gasoline motor fuel mixture which not only functions as a fuel, but also provides lubrication in a highly diluted form without the sump-type or crankcase lubrication system, is utilized. Many chain saw operators use special chain saw lubricating oil for this purpose. Moreover, manufacturers may provide chain saw lubricating oil in containers corresponding to the volume of the fuel reservoir to facilitate mixing the proper ratio of gasoline and lubricant.

When internal combustion engines of the type noted are operated in cold (approximately 40°F to sub-freezing temperatures), humid (approximately 50-100% relative humidity), weather, or in a cold humid environment immediately surrounding the engine, a stalling problem may be encountered. It has generally been recognized that repeated engine stallings under such cold, humid conditions may be caused by a formation of ice in the carburetor. The accumulation of this ice produces a blockage in the carburetor, most generally in the vicinity of the throttle, and may seriously interfere with the production of a fuel-air mixture suitable for combustion in the cylinder of the engine. It is known that gasoline evaporating in the carburetor has a sufficient refrigerating effect to condense and freeze the moisture present in air even in temperatures somewhat above the freezing temperature. As a result, ice particles may deposit along the interior of the carburetor, and as noted above, partially or completely block the air passage between the carburetor wall and the carburetor throttle valve with a resulting stalling. This stalling may be particularly pronounced when the chain saw engine is idling.

As noted above, the chain saw art has advanced to the state where many lumbering operations are conducted with internal combustion engine-operated, portable chain saws. Many of these logging operations take place in extremely cold or snowy climates, and excessive engine stalling as a result of ice formation in the carburetor may be a source of serious annoyance and expense with a resulting increased fuel consumption, inconvenience and delay of frequent restarting. More-

over, the stalling of a chain saw engine in the mid-felling a tree may impose a serious safety hazard where precise timing is critical to control of the fall.

A variety of methods and apparatus presently exist for heating the carburetor of a chain saw engine to prove operation under relatively cold weather conditions. For example, a closed circuit, radiator-type system, which has been found to be particularly effective for preheating the air which is passed to the carburetor air inlet of the engine, is disclosed in a U.S. Zimm et al. Pat. No. 3,498,280. In addition, a method and apparatus for utilizing a stream of exhaust gas, which is generated by a chain saw engine, by directing the stream, as a free flow, through air towards a selected location on a chain saw is disclosed in a U.S. Loop Pat. No. 3,678,973.

While these prior concepts are individually unique and advantageous, there has remained a need for additional techniques which would be operable to facilitate the operation of chain saws under cold weather conditions. Since compactness and simplicity have become some of the primary characteristics of modern chain saws, it has become desirable, in coping with the icing tendencies, to provide a solution to such problems without engendering structural complexity and added fabrication costs.

It is, therefore, a general object of the present invention to provide a method and apparatus for inhibiting the formation of ice in the carburetor of a two-cycle chain saw engine which minimizes or reduces the problems and limitations previously existing in the prior art.

It is a more particular object to provide a method of operation of a two-cycle chain saw engine which eliminates the use of an ice inhibitor to substantially prevent the formation of ice inside a carburetor of a two-cycle chain saw engine.

It is also an object of the present invention to provide an engine for a chain saw and other devices which may be operated in a cold, humid or snowy environment without an external carburetor heating means to inhibit the formation of ice in the carburetor thereof.

Another object of the present invention is to provide a method of inhibiting the formation of ice in the carburetor of a two-cycle chain saw engine which may be employed without requiring modification of the conventional chain saw structure.

An additional object of the present invention is to provide a method which minimizes trouble to a saw operator whereby an ice inhibitor may be introduced inside the carburetor of an engine for a chain saw or, say, a snowmobile during operation of the engine by means of an additive premixed with the cutting oil for the engine, which ice inhibitor substantially prevents the formation of ice in the carburetor in an amount sufficient to induce stalling of the engine.

A method and apparatus for inhibiting the formation of ice in a two-cycle chain saw engine according to the preferred embodiment of the present invention is intended to accomplish at least some of the foregoing objects. It includes a chain saw having a frame, a cutting chain connected to the frame, a cutting chain trained around the outside of the cutter bar, and a two-cycle reciprocating piston internal combustion engine connected to the frame for selectively driving the cutting chain. It will, of course, be appreciated that a rotary piston internal combustion engine could be used in the practice of this invention. The internal combustion engine has a carburetor in-

an interior portion comprising an induction passage, a throttle valve, a venturi throat which is defined by a portion of the induction passage and the throttle valve, and a choke plate. An ice inhibiting means is mixed with the fuel and lubricating fluid and introduced into the interior portion of the carburetor in which ice may form in conjunction with the combustible mixture of fuel, lubricating fluid and air. That is to say, during the operation of the engine, the ice inhibiting means is carried through the carburetor with the combustible mixture. As the mixture passes through the carburetor, ice is substantially prevented from forming within the interior of the carburetor. By introducing the ice inhibitor into the interior of the carburetor in such a manner to prevent the ice from forming, blockage of the carburetor from ice deposits is substantially prevented. An ice inhibiting means intended to accomplish at least some of the foregoing results may include, but is not limited to, hexylene glycol (i.e., 4-methyl-2,4-pentanediol).

Other objects and advantages of the present invention will become apparent with reference to the following detailed description of a preferred embodiment thereof in connection with the accompanying drawings, in which:

BRIEF DESCRIPTION OF THE DRAWINGS

FIG. 1 is a partial sectional view of a chain saw according to the present invention;

FIG. 2 is a schematic sectional view of the carburetor of the chain saw of FIG. 1 wherein an ice inhibiting means has been introduced; and

FIG. 3 is a schematic sectional view of a carburetor in the prior art wherein deposits of ice have accumulated to block flow through the carburetor.

DETAILED DESCRIPTION OF A PREFERRED EMBODIMENT OF THE INVENTION

Referring now to the drawings, wherein like reference characters have been applied to like parts throughout, in FIG. 1 there is illustrated a chain saw 10 having a guide bar 12 supporting a cutter chain 14. A handle 16 provides a trigger-type, throttle lever 18. A two-cycle, internal combustion engine 20 serves to impart power to the cutter chain 14 so as to cause the chain 14 to traverse or train around the periphery of the guide bar 12. A drive connection interposed between the engine and the cutter chain may include a conventional, pull-type starter. Alternatively, an electrical self-starting system (not shown) may be provided.

In any event, this structure is now well known in the chain saw art. It corresponds, in general, for example, to the basic structure described in a publicly available McCulloch Shop Manual associated with the Mac 1-10 and 2-10 chain saw manufactured by the McCulloch Corporation, Los Angeles, Calif.

The chain saw may further include a fuel tank 22, and an engine mounting bracket 24. The bracket may comprise an integral portion of a casting or may be a molded portion of a fuel tank 25. An upper portion 26 of the chain saw 10 comprises an enclosure 28. The enclosure 28 provides a carburetor housing cavity 30, the lower end portions of which are defined by enclosure walls 34.

A conventional carburetor 36 is positioned in the cavity 30 and is disposed in air flow transmitting com-

munication with an inlet passage 38 in a now well-known manner.

An upper portion 40 of the carburetor 36 contains a conventional opening 42 leading to an air transmitting or carburetor induction passage 44.

The carburetor 36 is secured to the engine 20 with the induction passage 44 connected to an engine inlet 56 which communicates with the crankcase of the engine 20. The upper portion of the cavity 30 may be closed by a preformed, foraminous air filter 46.

Turning now to FIG. 2, there is schematically depicted the carburetor 36 of the engine 20 illustrated in the chain saw 10 of FIG. 1. The carburetor 36 includes a carburetor body 48, having an induction passage 44 therethrough which includes an air inlet portion 50 and a mixture outlet portion 52 with a venturi 54 interposed therebetween and connecting the passage portions 50, 52. By having the diameter of the inlet portion 50 the same as that of the outlet portion 52, improved operation may be obtained.

The flow of fluid through the induction passage 44 is controlled by means of a throttle plate or valve 60 of the butterfly type, which is mounted on a throttle shaft 62.

25 Means for providing a suitably rich mixture for cold starting and warm up is provided by a butterfly type of choke plate or valve 64 which is mounted on the shaft 66. Means are also provided by idle fuel jet 65 for supplying fuel to the carburetor when the engine is idling. 30 The choke valve 64 is disposed in the air inlet portion 50 of the induction passage 44 and may be of the same diameter as the throttle valve 60. Any suitable well-known means may be used for rotating the choke valve shaft 66 so that the choke valve will be moved to a 35 closed or open or intermediate position.

These components thus far described are now well known. There will now be described a unique concept for inhibiting the formation of ice in the carburetor. As noted above, carburetor icing has continued to be a problem in the operation of chain saws utilizing two-cycle internal combustion engines where the chain saw is operated in a relatively cold and humid environment. When the chain saw 10 is operated in such a cold, humid environment without provision for anti-icing, ice 45 may accumulate within the interior portion of the carburetor and particularly may accumulate on the throttle plate 60 as shown in FIG. 3. Many icing problems occur when the throttle plate 60 is in or near the closed or idle position. Under these conditions, little, if any, fuel is discharged by the main jet (not shown) of the carburetor. During idling of the engine, ice formation may occur, above, below and in the small opening between the throttle plate 60 and the carburetor wall. 50 In addition, any ice which does accumulate on the throttle plate when it is open tends to obstruct the idle air flow when the throttle is closed. Hence this accumulation may be sufficient to appreciably block the flow of combustible fuel mixture through the carburetor with a result in rough engine operation and stalling.

55 The present invention functions to inhibit ice formation in the internal portion of the carburetor 10 and thereby substantially prevents ice crystals from accumulating on the induction passage surfaces to form a blockage.

60 As shown in FIG. 3, in the absence of the ice inhibiting means of the present invention, ice will generally form on edges 68 of the throttle plate 60 and can

spread progressively across the plate face 70. Simultaneously, ice may accumulate along the walls of the induction passage 44, especially while the engine is idling, when an increased fluid flow around the throttle may enhance the evaporation of gasoline and, hence, may produce an increased refrigerating effect. Without the use of anti-icing devices, ice formation may accumulate both on the throttle plate 60 and along the side walls of the carburetor in such a manner as to restrict the flow of combustible mixture. Such a restriction may result in engine stalling or rough operation, and the chain saw will often fail to perform until the blockage is removed.

While there is no intention to be bound by theoretical considerations, it appears that the ice inhibitor may lower the freezing point of water in the internal portions of the carburetor to a temperature below that which would ordinarily occur in the carburetor of a two-cycle chain saw engine operating in a cold, humid environment. In addition, or alternatively, the ice inhibitor may provide a film on the internal portions of the carburetor as it passes in contact therewith preventing an adhesion of ice crystals thereon. Regardless, a two-cycle chain saw engine according to the present invention has a substantially lower tendency towards formation of ice within the interior portions of the carburetor and a correspondingly lessened tendency towards engine stalling under conditions in which ice may form.

While ice crystals may not be absolutely prevented from forming in the carburetor, the present invention prevents any ice crystals which may form from accumulating in a manner which will restrict the flow of fluid through the carburetor body. As indicated in FIG. 2, occasional ice particles 72 may still form in the induction passage 44. However, the effect of the ice inhibiting means is sufficient to prevent a blockage or to otherwise interfere with the operation of the chain saw. Normally, the small particles of ice which may form notwithstanding the presence of the ice inhibiting means simply pass into the crankcase of the engine where they are almost instantaneously vaporized because of the relatively high temperatures therein.

During operation of the engine, an ice inhibiting means is introduced into the carburetor by means of the fuel supply system. The ice inhibiting means is mixed with the fuel-lubricating oil mixture of the two-cycle chain saw engine in an amount sufficient to inhibit the formation of ice within the carburetor of the engine without, however, appreciably adversely affecting the combustibility or volatility of the mixture to be ignited in the engine cylinder which amount, in the case of hexylene glycol as the ice inhibiting means, may be from about 0.1 to 0.2 % by volume of the fuel. The ice inhibiting means preferably is premixed with the lubricating oil (which premix is thereafter mixed with gasoline to provide the combustible mixture which is exploded in the engine cylinder) to facilitate mixing the correct proportion of ice inhibiting means. The concentration of inhibitor in the oil may depend also upon the ratio of oil to gasoline recommended by the manufacturer of the lubricant. In the case of hexylene glycol used with oil intended to be mixed in the proportions of 40:1 (1 volume of oil to 40 volumes of gasoline), the concentration of inhibitor in the oil will range from about 4 to 8%.

It will be appreciated that in utilizing the novel method and apparatus for inhibiting carburetor icing a chain saw engine according to the present invention certain significant advantages are provided.

In particular, the present invention eliminates a need for structurally complex heating apparatus to increase the temperature of the carburetor walls or of the intake air to the carburetor as well as the need for an exterior heater or for pre-operation modifications which may increase the cost and complexity of the chain saw engine. The ice inhibitor of the present invention may be used when weather or temperature conditions so require it and may otherwise not be used. Hence, the invention is provided a maximum of flexibility of operation with a minimum of complexity and cost.

Of further significance is the fact that the ice inhibitor may be introduced into the fuel system of a chain saw engine by means of the lubricating oil. This assures that the proper proportion of ice inhibitor is used to inhibit icing while, at the same time, there is an assurance that the fuel volatility is not interfered with. Such an arrangement permits improved operation of a chain saw in a cold environment, and, in commercial situations such as logging operations, may substantially increase the efficiency of chain saw use.

Thus, it is apparent that there has been provided, in accordance with the invention, a method and apparatus for inhibiting icing in the carburetor of a two-cycle chain saw engine that substantially satisfies the objects and advantages set forth above. Although the present invention has been described in conjunction with a specific embodiment it is evident that many alternative modifications, and variations will be apparent to those skilled in the art in light of the foregoing disclosure of the invention. Accordingly, it is intended that all such alternatives, modifications, and variations which fall within the spirit and scope of the invention as described in the appended claims be embraced thereby.

What is claimed is:

1. A method for operating a chain saw in an environment where ice may be formed in a carburetor thereof, and wherein said chain saw comprises: a two-cycle, internal combustion, chain saw engine; a cutter chain drivenly engaged with said chain engine; a reservoir means connected to said chain saw engine and operable to contain a combustible lubricating oil-gasoline mixture for transmittal to a carburetor means; carburetor means for transmitting a volatile mixture of air and said lubricating oil-gasoline mixture therethrough for passage to a combustion chamber of said chain saw engine; and said carburetor means having an interior portion including an induction passage; said method comprising:
  - a. storing an ice inhibiting means with a lubricating oil composition;
  - b. maintaining a ratio of said ice inhibiting means to said lubricating oil composition so as to ensure that when said lubricating oil composition is added in a predetermined lubricating ratio to said gasoline, the ratio of ice inhibiting means to gasoline will automatically be provided which will substantially prevent the formation of ice when said gasoline is drawn through said induction passage with air.

- temperature of less than about 40°F and having a relative humidity of greater than about 50%;
- c. concurrently mixing said lubricating oil composition and ice inhibiting means with gasoline to provide a combustible lubricating oil-gasoline mixture containing an ice inhibiting means mixed therewith, and simultaneously
- i. condition said gasoline for effective lubrication and combustion in said two-cycle, internal combustion chain saw engine, and
- ii. condition said gasoline to prevent the formation of ice when said gasoline is drawn through said induction passage with air at a temperature of less than about 40°F and having a relative humidity of greater than about 50%;
- d. providing, in said reservoir means, said combustible lubricating oil-gasoline mixture containing an ice inhibiting means mixed therewith and operable to substantially prevent the formation of ice within said induction passage of said carburetor means during operation of said chain saw engine in an environment where ice may be formed in said carburetor means and where said mixture is drawn through said induction passage with air at a temperature of less than about 40°F and having a relative humidity greater than about 50%;
- e. operating said chain saw engine to pass said combustible mixture through said carburetor means of said chain saw engine and thereby introduce said

- ice inhibiting means into said induction passage of said chain saw engine to substantially inhibit a formation of ice therein and prevent an ice blockage in said induction passage when said chain saw engine is operated in an environment where ice may be formed in said carburetor means, and where said mixture is drawn through said induction passage with air at a temperature of less than about 40°F and having a relative humidity greater than about 40%;
- f. said combustible lubricating oil-gasoline mixture, containing said ice inhibiting means, being contained within said reservoir means during said operation of said chain saw while being subject to chain saw operation-induced vibration;
- g. said volatile mixture of air and lubricating oil-gasoline mixture being transmitted through said induction passage of said chain saw engine carburetor means with said ice inhibiting means while said induction passage is subject to said chain saw operation-induced vibration; and
- h. said volatile mixture of air lubricating oil-gasoline mixture, including said ice inhibiting means, being transmitted from said induction passage through a crank case of said chain saw engine prior to combustion of said volatile mixture in said combustion chamber of said chain saw engine.
